UNITED STATES PATENT OFFICE.

KENNETH MACOMB CHANCE, OF LONDON, ENGLAND, ASSIGNOR TO THE BRITISH CYANIDES COMPANY, LIMITED, OF LONDON, ENGLAND.

MANUFACTURE OF SULFOCYANIDS.

No. 922,564.

Specification of Letters Patent.

Patented May 25, 1909.

Application filed January 6, 1909. Serial No. 470,909.

To all whom it may concern:

Be it known that I, KENNETH MACOMB CHANCE, director, a subject of the King of Great Britain, residing at 49 Queen Victoria street, in the city of London, England, have 5 invented new and useful Improvements in and Relating to the Manufacture of Sulfo-Cyanids, of which the following is a specification.

10 The United States Patent No. 705,152, of July 22, 1902, describes the extraction of cyanogen from coal gas by scrubbing the gas with ammoniacal or gas liquor or water and sulfur.

15 In carrying out the invention described in that patent it has hitherto been deemed necessary to scrub the gas in a costly and complicated scrubber of the type commonly used for extracting ammonia from coal gas. I 20 have found that such scrubbers besides involving considerable initial outlay are costly to maintain in good working order because the complicated revolving apparatus of such scrubbers are, when sulfur is employed, liable 25 to great wear and tear and to break down with consequent stoppage of the working of the plant.

I have found that in working with gas from which the tar has already been industrially extracted there generally remains sufficient tar to form a coating upon the sulfur which is being agitated in presence of the gas containing cyanogen and this tar coating impedes the effective formation of polysulfids and consequently the subsequent formation 30 of sulfocyanids. I have also found that in some gas works where the tar is present in still greater quantity the effective working of the scrubbing apparatus is liable 35 to be greatly impeded and even stopped by the tar in question. Hence it is very desirable 40 to remove as far as possible the last traces of tar from the gas previous to passing it through liquor in which sulfur is being 45 agitated.

The accompanying drawing is a vertical section showing an apparatus for the purification of coal gas.

50 *a* is the inlet through which the gas is brought to the chamber *b* from which a number of pipes *c* with serrated or perforated ends deliver it beneath the surface of the liquor contained in the first tank *d* from which it passes by the pipe *e* to the chamber

f from which again a number of pipes *g* deliver it beneath the surface of the liquor in the second tank *h* in which is a stirrer *i*.

j is the exit pipe and *k* is a hopper by means of which sulfur and liquor may be introduced into the tank *h*.

60 From the tank *h* a pipe *l* leads to a vessel *m* in which is a downflow pipe *n* leading to the tank *d*. The height of this pipe can be adjusted so as to regulate the rate of flow from the tank *h* to the tank *d*, such flow being 65 due to the condensation from the gas or to the addition of fresh liquor.

o is a pipe putting the vessel *m* into communication with the tank *h* above the level of the liquor so as to equalize the pressures. A 70 similar arrangement *p* may be used for the overflow of the liquor from the lower tank.

By the present arrangement of apparatus such removal is effectively brought about.

I first wash the gas in a liquor in which 75 there is no free sulfur but which contains alkaline polysulfid in solution and next in ammoniacal or gas liquor or water together with free sulfur which is kept agitated by means of some simple stirring appliance.

80 In the first washing as above indicated the alkaline polysulfid reacts upon some of the cyanogen in the gas to form sulfocyanid. The sulfureted hydrogen thereby liberated 85 passes with the gas to the second washing compartment containing the sulfur where the sulfureted hydrogen combines with the ammonia and the sulfur to form ammonium polysulfid which removes the remainder of the cyanogen while some of the polysulfid is 90 in course led to the first vessel for use therein as above explained.

If it be considered desirable to employ this 95 washing apparatus for the production of sulfocyanids after instead of before the ammonia has been completely extracted from the gas it will then be necessary to introduce an alkaline base together with the sulfur.

100 While I wish to broadly claim this process for the simplified production of sulfocyanids from gas no matter what the particular form of apparatus adopted I have described an apparatus by the aid of which the process may be cheaply and effectively carried out.

105 What I claim is:

1. In the manufacture of sulfocyanid from gas, bringing the gas into intimate contact firstly with liquor containing a polysul-

fid and secondly with liquor which contains sulfur and is kept in agitation substantially as described.

2. In the manufacture of sulfocyanid from gas, bringing the gas into intimate contact firstly with liquor containing ammonium polysulfid and secondly with liquor which contains sulfur and is kept in agitation substantially as described.

10 3. In the manufacture of sulfocyanid

from gas, bringing the gas into intimate contact firstly with liquor containing a poly-sulfid and secondly with liquor which contains sulfur and an alkaline base and is kept in agitation substantially as described. 15

KENNETH MACOMB CHANCE.
